ABSTRACT

An antimicrobial and softening composition for laundry use comprises a water-soluble heavy metal-free non-oxidizing antimicrobial agent, and a glycamide of the formula:

wherein R_1 and R_2 are alkyl groups having a total of 23 to 39 carbon atoms, and n is 3 or 4, preferably 4.

4 Claims, No Drawings

ANTIMICROBIAL AND LAUNDRY SOFTENING COMPOSITIONS

RELATED APPLICATION

This application is a continuation -in- part of "Agent for the Post-Treatment of Laundry", filed July 26, 1967, the applicable priority document being on file in the parent application, Ser. No. 656,136, now U.S. Pat. No. 3,637,495.

THIS INVENTION

It has now been found that the glyciamides disclosed in the parent application can be used effectively with certain water-soluble antimicrobial agents to both disinfect and soften textile fabrics.

The glyciamides have the formula given in the Abstract of the Disclosure. Preferably R_1 represents an alkyl radical having 10 to 22, preferably 12 to 20, and most preferably 16 to 18 carbon atoms, R_2 represents an alkyl radical having 7 to 21, preferably 11 to 19, and most preferably 15 to 17 carbon atoms, and n is either of the whole numbers 3 or 4, further wherein the alkyl radical R_1 can be interrupted by an ether oxygen atom in the vicinity of the N-atom, and the sum of the carbon atoms contained in R_1 and R_2 amounts to at least 23 and preferably to from 27 to 35. Preferably $n = 4$, i.e., N-alkyl-N-acylglyciamines are employed as softening agents. The latter will hereinafter be called "glyciamides" for the sake of simplicity. The data given on the glycamide softening agents also apply accordingly to compounds wherein $n = 3$.

The term antimicrobial agents as used herein is understood to mean both bactericidal and bacteriostatic, and fungicidal and/or fungistatic products. The antimicrobial agents are required to be water soluble either per se or in the form of their salts. Examples of suitable antimicrobial agents for use herein are formaldehyde, halogenated phenols, nitrated mono- or polyalcohols, and antimicrobial surfactants.

The present composition can be used in the treatment of washed textiles, alone or together with other conventional laundry detergents and post-treatment agents, such as acidifiers or disincrusting agents, optical brighteners; and may be made and marketed in powdered or liquid form, as is customary.

The textiles fabrics or other laundered items which have been rinsed with the products fabrics of the invention, possess, after drying, not only a high degree of fullness and softness, but they also possess excellent absorbency. Furthermore, the softening agents of the invention are quite compatible with anionic optical brightening agents. If any of the above-mentioned antimicrobial agents are used, not only are any microbes that might be present in the washed textiles or in the rinse water killed, but often anti-microbial properties are conferred upon the post-treated textiles.

The glyciamides to be used in the method of the invention or contained in the preparations according to the invention can be prepared by amidation in the known manner from the appropriate glyciamines which can be produced by the hydrogenation of hexoses or their oligomers using therefor Raney nickel catalyst in the presence of higher alkyl amines.

The principal hexoses involved are monosaccharides such as glucose, mannose, galactose, fructose, sorbose or their mixtures such as invert sugar; however, their oligomers can also be used, such as maltose, for exam-

ple. Instead of hexoses, pentoses, mixtures of pentoses or mixtures of pentoses and hexoses can be used.

The amines suitable for use in the reaction are primary alkylmonamines. The alkyl radicals of these amines, like the alkyl radicals of the fatty esters to be used in the amidation, can be saturated or unsaturated, straight-chained or branched, and of synthetic or natural origin. The radicals R_1 present in the glyciamides can be derived from decyl, lauryl, myristyl, cetyl, stearyl, oleyl, arachyl, or behenyl amine. There are also suitable those amines whose carbon chain is interrupted by an ether oxygen atom in the vicinity of the N-atoms, preferably between carbon atoms 2 and 3 or 3 and 4 (counting from the N-atom). Such amines, in which the NH_2 group and the ether oxygen atom are separated from one another by three carbon atoms, are obtained for example by addition of acrylonitrile to a suitable fatty alcohol followed by reduction of the nitrile group.

The fatty acid radicals R_2-CO- can be derived from capric, lauric, myristic, palmitic, stearic, arachic or behenic acid. Glyciamides can also be used in which the amine and/or the fatty acid radicals are present as isomer mixtures, such as those which can be obtained from fats of natural origin. Accordingly, these amines and fatty esters can be made from the fats derived from plants, land or marine animals, as for example, from coconut oil, palm oil, linseed oil, cottonseed oil, peanut oil, rapeseed oil etc., from hog lard, tallow or fish or whale oil or from fractions of the fatty acids contained in these fats. The amines or fatty esters to be used are not to be excessively unsaturated i.e., they are not to have an iodine number higher than 50, and preferably not higher than 30. In fact, even substantially completely hardened products having iodine numbers below 10 and preferably below 5 can be used.

The methyl esters which are employed are preferably fatty acid esters. There can, however, be used to equal advantage the esters of monoalcohols having two to four carbon atoms, as for example, the esters of ethyl, propyl, isopropyl, butyl and isobutyl alcohol etc. Suitable for use herein are also the fatty acid glycerides.

The amidation of the alkylglyciamines is carried out by heating the fatty esters with the amines at temperatures of 150° to 170°C, preferably with agitation. The course of the reaction can easily be observed by intercepting the alcohol released by the reaction. When the amount of liberated alcohol has reached approximately the theoretical, the reaction is stopped. In no case is the reaction mixture or the reaction product that has been formed to be heated so intensely or so long as to produce dehydration.

The glycamide thus obtained can be used directly for the purposes of the invention. If desired, however, it can first be purified, as for example by recrystallization. The glyciamides are moderately soluble in water, but are readily soluble in water-soluble organic solvents, such as univalent or polyvalent alcohols having one to four carbon atoms, or in ether alcohols, such as the monoethers formed by reaction of the above-mentioned univalent alcohols with ethylene glycol, diethylene glycol, propylene glycol, butylene glycol, or by the monoethers or diethers of the said univalent alcohols formed by reaction of the univalent alcohols with glycerine. The glyciamides are also soluble in the lower water-soluble ketones. The aforesaid solvents, particularly those having boiling points below 100°C,

are also suitable for the recrystallization of the glyciamides.

In accordance with the invention, the washed textiles or other laundered items are contacted with a rinse water containing the glyciamides in concentrations of approximately 0.05 to about 2 grams per liter and preferably from 0.1 to about

The glyciamides can be used directly in the first rinse, even if the remains of the washing medium have not been completely washed out of the goods. Since, of course, it has become an established practice to add the softening agent to the final rinse, the same can, obviously be done when using the glyciamides of the invention or the softening agents containing them.

After the rinse, as effected in accordance with the invention, the laundry is dried in the conventional manner. The laundry is soft and full and has a pleasant feel, which becomes pleasantly observable especially in the case of articles which come in contact with the skin, such as underwear, bed linen and handkerchiefs. In particular, wash and drying cloths exhibit a remarkably good absorbency, which is greatly appreciated in the case of dishtowels and bath towels. Further the moist articles which have been soft-rinsed according to the invention yield their moisture more quickly than others on being subjected to drying. Finally, the textiles thus treated are observed to iron more easily than the conventionally laundered articles.

Since the glyciamides act on the textiles or other laundered items for only a relatively short period especially in the case of automatic washing machines, it is advantageous to use the moderately water-soluble glyciamides in finely divided form. This is accomplished in accordance with the invention by using the post-treatment agents in solid or liquid form and in a form in which the glycamide is mixed together with the conventional solid or liquid diluents and/or fillers.

Water-soluble inorganic, preferably weakly alkaline, neutral or weakly acid substances are suitable for use as solid fillers. For the manufacture of solid preparations, inorganic or organic salts are of primary importance, as for example the alkali salts of sulfuric acid, orthophosphoric acid or pyrophosphoric acid. However, salts of organic acids can also be used, such as the non-surface-active salts of carboxylic acids or hydroxycarboxylic acids having one to 10, preferably one to six carbon atoms, as for example, salts of acetic acid, propionic acid, lactic acid, citric acid, tartaric acid, benzoic acid, phthalic acid, etc. Water-soluble inorganic or organic acid amides or their salts may also be present as solid fillers, as for example, amidosulfuric acid salts, amidophosphoric acid salts and water-soluble amides or carboxylic acids, such as urea, acetamide, etc. Solid polyethylene glycols are also usable as fillers.

The solid post-treating agents of the invention can be prepared for example by spraying a solution or dispersion of the glyciamides in a suitable liquid onto the finely divided solid filler substances. It is also possible to spray aqueous solutions or suspensions of glyciamides having a percentage of fillers dissolved or dispersed therein, in the known manner, and thus to obtain readily soluble powders or granules. Lastly, solutions or dispersions of the glyciamides in fused urea or in fused polyethylene glycols can be sprayed or otherwise converted into easily soluble powders or granules.

The time which is required for the glyciamides added as concentrates to the rinse water to reach the desired

concentration for use can be still further reduced by using liquid products in which the glyciamides are dissolved in a solvent or dispersed in water. In this manner no time is lost i.e., taken up in the dissolution of a solid filler, and instead the desired concentration for use establishes itself immediately after the addition of the liquid concentrate to the rinse water.

The liquid aqueous concentrates are prepared by dispersing the moderately water-soluble glyciamides in an aqueous phase. It has proved advantageous for the glyciamides first to be dissolved in one of the above-named water-soluble organic solvents and thereafter for the resulting solutions to combine with water. The solid glyciamides thereupon separate in finely divided form, the organic solvents serving as solubilizers. These aqueous solutions can of course contain any of the above-named solid fillers if the stability of dispersion is not adversely affected thereby. In many cases the stability may be improved by such addition. For this purpose, the alkali salts of lower carboxylic acids or hydroxycarboxylic acids containing up to 6 carbon atoms, and urea or acetamide have proved particularly suitable and can be used instead of, or together with the above-mentioned water-soluble organic solvents serving also as solubilizers.

The known dispersing and emulsifying agents or emulsion stabilizers can be used for effecting the stabilization of the aqueous glycamide dispersions.

Suitable dispersing or emulsifying agents include the known anionic or non-ionic wash-active substances whose action is based on the simultaneous presence of one hydrophobic and one hydrophilic radical in their molecules. The hydrophobic radical consists usually of an alkyl radical having eight to 20, preferably 12 to 18 carbon atoms. Anionic or non-ionic groups are suitable as hydrophilic radicals. The anionic groups include carboxyl, sulfonic acid or sulfurnic acid semi-ester groups; the non-ionic groups include aggregations of hydroxyl groups or polyethylene glycol ether chains. Accordingly, alkylbenzenesulfonates, fatty alcohol sulfates, fatty alcohol glycol ether sulfates having one to five ethylene glycol ether radicals in the molecule, fatty acid monoglycerides, polyethylene glycol ethers of fatty alcohols or alkylphenols having five to 20 ethylene glycol ether radicals in the molecule are suitable for use as dispersing and emulsifying agents. In no case, however, must the amount of these dispersing and emulsifying agents be greater than the amount of the glycamide present and preferably the dispersing or emulsifying agent should be present in substantially lesser quantities amounting to at the most to 50%, and preferably amounting to from 5 to 25% of the glyciamides.

Suitable emulsion stabilizers include the water-soluble colloids, such as the salts of ether carboxylic acids or ether sulfonic acids of cellulose, cellulose sulfate, polyacrylic acid or polymethacrylic acid salts, water-soluble polyacrylamides and polyethylene glycols, preferably those having a molecular weight greater than 600, and particularly the solid polyethylene glycols. Many of these emulsion stabilizers produce a great increase in the viscosity of the aqueous solutions, and therefore they are used in quantities preferably of less than 1% so that the post-treatment agents will still be readily fluid in nature. Others, particularly the polyethylene glycols, can be used in substantially greater

quantities, without raising the viscosity to undesirable levels.

The glyciamides according to the invention and the compositions containing such glyciamides can advantageously be combined with other substances which have heretofore been used as post-treatment agents. These include, for example, optical brighteners, acidifying and disincrusting agents, colorants, perfumes, etc. These substances can be incorporated into the solid or liquid post-treatment agents according to the invention.

The combined use of the above-described softening agents with optical brighteners is to be considered as an important and novel feature of the invention. The brighteners are intended mainly for cellulose fibers, but brighteners for cellulose and/or other fibers, especially synthetic fibers, can be used as well.

Suitable additives for acidification and/or for the removal of ash or other fiber incrustations include the non-oxidizing acids which have been found to be not harmful to the fibers to be treated and particularly those additives which form soluble alkaline earth metal salts, and complex compound formers. The acid reacting substances include for example amidosulfuric acid, urea compounds or orthophosphoric acid or solid organic acids like citric acid. The complex compound formers include for example tripolyphosphates or the higher but still water soluble polyphosphates of alkalies, salts of nitrilotriacetic acid, ethylenediamine tetraacetic acid, N-oxyethylenediaminetriacetic acid and other conventional organic complex compound forming agents, such as the salts of certain di-, tri- or tetraphosphonic acids.

As instances of halogenated phenols which may be used as antimicrobials, there may be mentioned, for example, chlorination and bromination products of phenol, such as pentachlorophenol, and also halogenated cresols, xylenols, such as 4-bromo-3,5-xylenol or halogenated cyclohexylphenols, methylcyclohexylphenols or benzylphenols.

There may also be used the water-soluble antimicrobial substances of the cationic or hybrid ionic surfactant type, which serve in the final post-treatment agents also as dispersing agents.

Instances of cationic substances which are suitable as antimicrobials include quaternary ammonium compounds which contain on the nitrogen atom thereof an aliphatic hydrocarbon radical containing eight to 18, and preferably 10 to 14 carbon atoms, or alternatively contain on the nitrogen atom at least one aromatic radical or a radical having double bonds, the latter radical being linked to the nitrogen atom by an aliphatic carbon atom. The following are instances of the cationic compounds suitable for use in the invention include: diethylbenzyldecyl ammonium chloride, diethylbenzyloctyl ammonium chloride, and dibutylallyl, methylethylbenzyl, ethylcyclohexylallyl and ethylcrotyl-diethylaminoethyl decyl ammonium chloride.

There are also tertiary amines suitable for use which can be prepared by condensing a primary or secondary amine containing up to four basic nitrogen atoms and one aliphatic or alkylaromatic radical having eight to 18 and preferably eight to 14 aliphatic carbon atoms with a phenol or lower aliphatic aldehyde, preferably formaldehyde or acetaldehyde. The phenol employed in the condensation reaction may have in its molecule a plurality of sites capable of condensation, and these

may be substituted with lower alkyl, alkoxy or benzyl radicals containing up to four carbon atoms. The phenyl, alkyl, alkoxy and benzyl radicals may additionally be substituted with chlorine or bromine atoms and/or

5 with nitro groups. Examples of such condensation products include, for instance, the following compounds: oxybenzyloctylamine, oxybenzyldecylidethylenetriamine, (2-oxy-5-chloro-6-methylbenzyl)-dodecylidethylenetriamine, (2-oxy-5-methylbenzyl)octyldiethylenetriamine, (2-oxy-5-chloro-4,6-diethylbenzyl)octyldiethylenetriamine, (tris-oxybenzyl)-dodecyltriethylenetetramine, o,o-bis-(tetradecylaminomethyl)-p-cresol, o,o-bis-(dodecylidethylenetriaminomethyl)-p-chloro-m-cresol, m,m-bis(dodecylidethylenetriaminomethyl)-p-oxybenzoic acid, 2,2-bis-p-oxy-m,m-di-(dodecylidethylenetriaminomethyl)-phenolpropane, o,o-bis-(dodecylidethylenetriaminomethyl)-p-nitrophenol, o,o-bis-(dodecylpropylenediaminomethyl)-p-chloro-m,m-dimethylphenol etc. The aforesaid tertiary amine compounds have a weakly acid reacting hydroxyl group and thus represent an intermediate type between the purely cationic and the hybrid-ionic surfactants.

25 The hydrid-ionic surfactants which have achieved particular importance as antimicrobials include compounds of the aminocarboxylic acid, polyaminocarboxylic acid and betaine type.

30 Illustrative of the aminocarboxylic and polyaminocarboxylic acid antimicrobial agents are compounds having the following structural formula:

35 wherein R_4 represents an alkyl or alkylaryl radical of high molecular weight, preferably such a hydrocarbon radical having six to 18 and most preferably eight to 14 aliphatic carbon atoms, R_5 represents an ethylene or propylene radical, x represents a whole number of from

40 1 to 6 and R_3 represents an aliphatic-aromatic or aromatic bridge having one to six carbon atoms. The following compounds are illustrative of aminocarboxylic and polyaminocarboxylic compounds having the above mentioned formula: dodecylaminopropylglycine, tetra-

45 decylaminoethyl- β -alanine, dodecyl-di-(aminoethyl)-glycine, dodecylaminoisopropylaminomethylsalicylic acid, hexadecyl-tri-(aminoethyl)- β -aminobutyric acid, dodecylbenzylaminopropyl- β -alanine, octylphenoxyethyl-di-(aminoethyl)-glycine, dodecylaminoethyl-phenylalanine, dodecylaminoethylaminobenzoic acid, etc.

50 The radical R_4 can also be interrupted by an ether oxygen atom, as is the case, for example, in the following compounds: dodecyloxypropylaminopropionic acid, lauryl-1,3-oxypropyl- β -aminobutyric acid, C_{12-14} -alkyloxyethylaminoacetic acid, dodecyl-1,2-oxypropylaminomethylsalicylic acid, octylphenoxyethylaminobenzoic acid.

55 The compounds that can be used according to the invention furthermore include carboxybetaines of the formula:

which can be used both in the betaine form, i.e., in the form of inner salts, and in the form of acidic or basic salts. R_4 has the same meaning as in the preceding formula, R_7 represents an ethylene or propylene group, and R_6 , R_8 and R_9 represent aliphatic bridges of low molecular weight, X an ether oxygen atom or the $-\text{CONH}-$ group. Examples of such carboxybetaine compounds are lauroyl-1,3-amidopropylidemethylaminoacetic acid, lauryloxyethyldi-(hydroxyethyl)-aminopropionic acid, octylphenoxyethyldi-(hydroxyethyl)-aminoacetic acid, etc.

The antimicrobial agents can be combined in any desired manner with solid or liquid diluents or fillers, with hydrotropic substances, with dispersing and emulsifying agents, with emulsion stabilizers, with brighteners and with acidification and disincrusting agents.

The amounts of the antimicrobial agents contained in the solid or liquid laundry post-treatment agents can vary within wide limits according to the subsequent intended use of the laundered articles, amounting to 0.5 - 30% and preferably 1 - 20% by weight. If the antimicrobial agents are hybrid-ionic surface active substances, their quantity is always smaller than the quantity of the softening agent; preferably the quantity of the hybrid-ionic surface-active antimicrobial agents amounts to no more than 50% of the quantity of the softening agent.

The laundry post-treatment agents according to the invention as noted above constitute solid products and as such have the following composition :

30 - 95 and preferably 70 - 90 wt-% of solid vehicle substance

70 - 5 and preferably 30 - 10 wt-% glycamide

0 - 20 and preferably 1 - 15 wt-% of an optical brightener, the same being present in a quantity amounting to 5 to 25% of the amount of glycamide present;

0 - 30 and preferably 1 - 15 wt-% of a surface active dispersing or emulsifying agent, the quantity thereof always being less than the amount of the glycamide and preferably no more than 50% and most preferably from 5 to 25% of the amount of glycamide;

0 - 20 and preferably 0.1 - 10 wt-% of an emulsion stabilizer or thickening agent, the quantity thereof being regulated so that a 10% aqueous solution or dispersion of the entire solid preparation will have a good fluidity;

0 - 30 and preferably 1 - 20 wt-% of at least one of the above-mentioned antimicrobial agents, with the proviso that if they are antimicrobial hybrid-ion surfactants, the quantity thereof is always to be smaller than the quantity of the glycamide, amounting preferably to no more than 50% and most preferably to from 5 to 25% of the quantity of the glycamide.

The liquid, laundry post-treatment preparations in accordance with the invention have the following composition :

2 - 30 and preferably 5 - 15 wt-% glycamide.

0 - 50 and preferably 5 - 30 wt-% solid water-soluble hydrotropic substance and/or water-soluble organic solvent.

0 - 10 and preferably 1 - 8 wt-% of an optical brightener but preferably such a quantity of optical brightener as to amount to 5 to 25% of the amount of the glycamide.

0 - 10 and preferably 0 - 5 wt-% of a surface active emulsifying or dispersing agent, the amount thereof always being less than the amount of glycamide and amounting preferably to no more than 50, and most preferably 5 to 25 wt-% of the amount of glycamide.

0 - 20 and preferably 0.1 - 10 wt-% of a water-soluble emulsion stabilizer or thickening agent, the quantity thereof, however, being regulated so that the final preparation will have good fluidity.

0 - 30 and preferably 1 - 20 wt-% of at least one of the above-named antimicrobial agents; if they are antimicrobial hybrid-ion surfactants, the quantity thereof always being less than the quantity of the glycamide, amounting preferably to no more than 50% and most preferably from 5 to 25% of the quantity of the glycamide. Balance water.

In the liquid preparations the water can be entirely replaced by water-soluble organic solvents, or at least to such an extent that all of the components and especially the glycamide, are dissolved.

The Examples given hereinafter serve to illustrate the invention without being in any way or form considered as limitative of the scope of the same.

The glycamides incorporated into the softening agents of the invention and tested in the manner to be described below were prepared on the basis of the following procedure:

30 In a three-necked flask equipped with a gas feed tube, agitator, condenser, and a receiver for the distillate, a mixture of 0.22 mole of N-alkylglycamine and 0.20 mole of fatty acid methyl ester was heated slowly under a current of nitrogen, with intense agitation, to 150° to 170°C. The methanol released in the reaction was distilled off and held in a graduated receiver. The reaction mixture was maintained at 150° to 170°C until about 75 to 80% of the theoretical amount of methanol had passed over. This required from 2 to 5 hours depending on the starting material. Thereafter the rest of the methanol was removed by two hours of heating in vacuo; the methanol was frozen out in a cooling trap. As soon as 94 to 98% of the theoretical amount of methanol had been recovered, the reaction was ended.

The N-alkyl-N-acyl glycamines thus prepared were in the form of pastes or solids, depending on the chain length and on the chain length distribution of the alkyl or acyl radicals. If desired, they could be purified by recrystallization from the water-soluble organic solvents mentioned previously, or from benzene or acetic acid ethyl ester.

The advantageous effects that are achieved with the aforesaid glycamides i.e. high degree of softness, fullness and absorbency were demonstrated in tests carried out on ordinary cotton fabrics and on cotton terrycloth fabrics, which tests are described fully in the parent application.

EXAMPLE 1

Glucamide $R_1 = C_{12}H_{25}$; $R_2 = C_{17}H_{35}$; Total 29 C atoms

Feel: 2.0

Compressibility:	Vertical Absorbency:	Absorption value:
$Z_{\text{av}} = 127$ $\Delta Z_{\text{av}} = 27$	$St_x = 68\%$ $66 St_y = 200\%$	$S_x = 75\%$ $\Delta S_y > 1700\%$

EXAMPLE 2

Glucamide $R_1 = C_{14}H_{29}$; $R_2 = C_{15}H_{31}$; Total 29 C atoms

Feel: 2.0

Compressibility:	Vertical Absorbency:	Absorption Value:
$Z_{\%} = 122$	$St_x = 52\%$	$S_x = 36\%$
$\Delta Z_{\%} = 22$	$\Delta St_x = 140\%$	$\Delta S_x > 800\%$

EXAMPLE 3

Glucamide $R_1 = C_3H_6OC_{16}H_{33}$; $R_2 = C_{15}H_{31}$; Total 34 C atoms

Feel: 1.5

Compressibility:	Vertical Absorbency:	Absorption Value:
$Z_{\%} = 132$	$St_x = 47\%$	$S_x = 23\%$
$\Delta Z_{\%} = 32$	$\Delta St_x = 120\%$	$\Delta S_x > 470\%$

EXAMPLE 4

Glucamide $R_1 = C_{16}H_{33}$; $R_2 = C_{11}H_{23}$; Total 27 C atoms

Feel: 1.0

Compressibility:	Vertical Absorbency:	Absorption Value:
$Z_{\%} = 143$	$St_x = 30\%$	Not determined because of lack of substance
$\Delta Z_{\%} = 43$	$\Delta St_x = 35\%$	

EXAMPLE 5

Glucamide $R_1 = C_{18}H_{37}$; $R_2 = C_7H_{15}$; Total 25 C atoms

Feel: 1.5

Compressibility:	Vertical Absorbency:	Absorption Value:
$Z_{\%} = 134$	$St_x = 36\%$	Not determined because of lack of substance
$\Delta Z_{\%} = 34$	$\Delta St_x = 61\%$	

EXAMPLE 6

Glucamide $R_1 = C_{12}^- C_{18}^-$ mixture of coconut fatty acids, avg. = about C_{13}

$R_2 = C_{15}^+ C_{17}^-$ mixture of tallow fatty acids, avg. = about C_{16}

Total about 29 carbon atoms

Feel: 1.0

Compressibility:	Vertical Absorbency:	Absorption Value:
$Z_{\%} = 143$	$St_x = 59\%$	$S_x = 67\%$
$\Delta Z_{\%} = 43$	$\Delta St_x = 180\%$	$\Delta S_x > 1500\%$

EXAMPLE 7

Glucamide $R_1 = C_{16}^+ C_{18}^-$ mixture of tallow fatty acids, avg. = about C_{17}

$R_2 = C_{11}^- C_{17}^-$ mixture of coconut fatty acids, avg. = about C_{13}

Total about 30 C atoms.

Feel: 1.0

Compressibility:	Vertical Absorbency:	Absorption Value:
$Z_{\%} = 144$	$St_x = 34\%$	$S_x = 20\%$
$\Delta Z_{\%} = 44$	$\Delta St_x = 60\%$	$\Delta S_x > 400\%$

EXAMPLE 8

Fructamide $R_1 = C_{12}^- C_{18}^-$ mixture of coconut fatty acids avg. approx. C_{13}

$R_2 = C_{15}^- C_{17}^-$ mixture of tallow fatty acids avg. approx. C_{16}

Feel: 1.0

Compressibility:	Vertical Absorbency:	Absorption Value:

$Z_{\%} = 147$
 $\Delta Z_{\%} = 47$

$St_x = 40\%$
 $\Delta St_x = 79\%$

$S_x = 23\%$
 $S_x > 470\%$

EXAMPLE 9

Glycamide mixture from invert sugar

$R_1 = C_{12}^- C_{18}^-$ mixture 18^- coconut fatty acids, avg.

approx. C_{13}

$R_2 = C_{15}^- C_{17}^-$ mixture of tallow fatty acids, avg.

approx. C_{16}

Total approx. 29 C atoms

10 Feel: 1.0

Compressibility:

$Z_{\%} = 155$

$\Delta Z_{\%} = 55$

Vertical Absorbency:

$St_x = 46\%$

$\Delta St_x = 100\%$

Absorption Value:

$S_x = 23\%$

$S_x > 490\%$

EXAMPLE 10

Glycamide mixture from invert sugar

$R_1 = C_{16}^- C_{18}^-$ mixture of tallow fatty acids avg.

approx. C_{17}

$R_2 = C_{11}^- C_{17}^-$ mixture of coconut fatty acids avg.

approx. C_{12}

Total approx. 29 C atoms

Feel: 1.0

because of insufficient substance

EXAMPLE A

A post-treatment agent according to the invention for use with textiles having the following composition was prepared:

10 wt-% glucamide according to Example 6

30 wt-% isopropanol

2 wt-% ethoxylated dimethylpolysiloxane

1 wt-% 2-bromo-2-nitro-propanediol-1,3

10 wt-% tartaric acid

47 wt-% water

EXAMPLE B

A post-treatment agent for use with conventional laundry having the following composition was prepared:

10 wt-% glucamide according to Example 1

60 wt-% isopropanol

2 wt-% ethoxylated dimethylpolysiloxane

2 wt-% N-dodecyl-N-benzyl-N,N-dimethyl ammonium chloride 10 wt-% tartaric acid

16 wt-% water

The glycamide incorporated into the preparations of Examples A and B are replaced by any of the compounds of Examples 2-5 or 7-10, to secure after-rinsing agents having a similar action

We claim:

1. A laundry textile antimicrobial and softening composition consisting essentially of 0.5 to 30 weight percent of a water-soluble, heavy metal-free, non-oxidizing antimicrobial agent selected from the group consisting of nitrated polyalcohols and a quaternary ammonium compound, and about 2 to 70 weight percent of a textile fabric softening glycamide of the formula:

wherein:

R_1 = (1) alkyl of 10 to 22 carbon atoms or, (2) alkyl of 10 to 22 carbon atoms with an ether oxygen linkage between either the two and three or 3 and 4 carbon atoms from the nitrogen atom,

R_2 = alkyl of seven to 21 carbon atoms,
 $R_1 + R_2$ have 23 to 39 carbon atoms.

2. The composition of claim 1 in solid form wherein said glycamide comprises 10 to 30 weight percent thereof.

3. The composition of claim 2 in the form of a solution wherein said glycamide comprises 2 to 30 weight percent thereof, and, other than said antimicrobial agent, the balance being water or a water-soluble or-

ganic solvent selected from the group consisting of unsubstituted aliphatic monohydric alcohols of one to four carbon atoms, ether alcohols thereof formed by the reaction of said aliphatic alcohols with a glycol selected from the group consisting of ethylene glycol, diethylene glycol, propylene glycol, and butylene glycol, lower ketones, and monoethers or diethers formed by reacting said aliphatic alcohols with glycerine.

4. The composition of claim 3 wherein said nitrated 10 polyalcohols is 2-bromo-2-nitro-propanediol - 1, 3, and wherein said quaternary ammonium compound is N-dodecyl-N-benzyl-N, N-dimethyl ammonium chloride.

UNITED STATES PATENT OFFICE
CERTIFICATE OF CORRECTION

Patent No. 3,764,531

Dated October 9, 1973

Inventor(s) Hans-Werner Eckert et al.

It is certified that error appears in the above-identified patent
and that said Letters Patent are hereby corrected as shown below:

Col. 3, line 7 after "about" insert -- 0.5g/l --.

Col. 8, line 67, under "Absorption Value" change " 75% "
to -- 73% --.

Col. 8, line 68, Under "Vertical Absorbency" change "66" to
-- Δ --.

Col. 10, line 5 cancel " 18" and substitute -- of --.

Col. 11, line 9 (Claim 2, line 1) cancel "in solid form";

Signed and sealed this 23rd day of July 1974.

(SEAL)
